UNITED STATES PATENT OFFICE.

ROBERT L. SHEETZ, OF SIOUX CITY, IOWA.

VAULT-DOOR-UNLOCKING DEVICE.

Application filed August 28, 1925. Serial No. 53,147.

My invention relates to a vault door unlocking device such as illustrated in my Patent No. 1,547,452, issued July 28, 1925, and has for its object to provide such an unlocking device embodying improved features of construction enhancing the safety of the device, and minimizing the possibility of the device being rendered inoperative by bandits.

More particularly, it is my object to provide such an unlocking device in which means controlled from the inside of the vault door are provided, with which means a person locked on the inside of a vault may disconnect the pressure bar hand wheel from the pressure bar hand wheel shaft to prevent the said shaft being locked against rotation by the securing of the hand wheel to the vault door, or the otherwise locking of the hand wheel against rotation.

A further object of the invention is to hide that portion of the unlocking mechanism which is accessible from the inner side of the vault door by a simple device fashioned to resemble one of the common appendages ordinarily present on the inner side of the vault door, such as a bolt head or the like.

A further object is to provide an unlocking device having the above features, which is of simple, durable and inexpensive construction.

With these and other objects in view, my invention consists in the construction, arrangement and combination of the various parts of my device, whereby the objects contemplated are attained, as hereinafter more fully set forth, pointed out in my claims and illustrated in the accompanying drawings, in which:

Fig. 1 is an elevation of a portion of the front side of a vault door, illustrating a portion of the pressure bar system to which my invention is applied.

Fig. 2 is a horizontal sectional view illustrating the unlocking mechanism and hand wheel release, taken on the line 2-2 of Fig. 1.

Fig. 3 is an end view of the hand wheel hub.

Fig. 4 is an end view of the hand wheel shaft.

Fig. 5 is a view illustrating the unlocking wrench.

Fig. 6 is a view illustrating the release wrench, the socket thereof being shown in section.

Fig. 7 is a sectional view taken vertically through a different form of the central pressure bar gear box illustrating a modification of the unlocking and release mechanism adapted to that type of pressure bar mechanism.

Fig. 8 is a horizontal sectional view of the same, taken on the line 8-8 of Fig. 7.

Fig. 9 is a detail view of a modified form of the concealing device.

In view of the increased number of daylight robberies at the present time, the need for an effective and safe means for allowing the escape of persons locked within a vault having a pressure bar system, has become more urgent than formerly. An objection to the simple type of unlocking means wherein in the end of the pressure bar hand wheel shaft is made accessible to a wrench or the like from the inside of the door lies in the possibility of the bandit boring through the web of the hand wheel and tapping a bolt through the opening thus formed into the vault door, or tying a cable around the spokes of the hand wheel and securing it to a projecting portion of the door, so as to in either case lock the hand wheel shaft against rotation, and thus prevent the actuation of the unlocking means from the inside of the door.

The present invention contemplates primarily to provide means for releasing the hand wheel from its driving connection with the shaft so that even though the hand wheel may be locked against rotation, the shaft may still be rotated and the pressure bar mechanism thus actuated.

In Figs. 1 and 2 I have shown a portion of the common type of pressure bar mechanism, in which the vault door is indicated at 10, the central gear box at 11, the vertical connecting shaft at 12, and one of the horizontal pressure bars at 13. The pressure bar, 13, is geared in the ordinary manner by means of a bevel gear, 14, meshing with a bevel gear, 15, on the connecting shaft, 12, within a gear casing, 16.

In practically every form of pressure bar system, the combination box, 11, has a rear wall, 17, a side flange, 18, through which bolts, 19, are extended into the vault door to secure the box, 11, to the vault, and has a removable cover plate, 20, closing its open forward side. Bolts, 21, secure the plate, 20, to the box.

10 A hand wheel shaft, 22, is journaled in the rear wall, 17, and extends through the cover plate, 20. The shaft, 22, ordinarily terminates at the forward face of the door, 10:

15 A worm, 23, is pinned to the shaft, 22, and meshes with a worm gear, 24, on the connecting shaft, 12. A hand wheel, 25, is ordinarily keyed to the shaft, 22, by means of a key (not shown in the drawings) received in registering slots in the hub, 26, of the hand wheel and in the shaft, 22, respectively. 20 The outer end of the shaft, 22, may be provided with a threaded stud, 27, to receive a cap nut, 28, or may be tapped out to receive a cap screw, as the case may be, to cover the end of the shaft and retain the hand wheel against longitudinal movement on the shaft. 25

It will be understood that the parts heretofore described are of the ordinary pressure bar mechanism.

In the practice of my invention, the shaft, 30 22, is temporarily removed and its inner end provided with a transverse slot, 29, shown in Figs. 2 and 4. An opening, 30, is extended through the door, 10, coaxial with the shaft, 22, in order that the wrench, 31, may be inserted through the door, and its flattened end, 32, received in the transverse slot, 29, of the shaft, 22. It will now be seen that should a banker be locked within a vault having a pressure bar system, and the pressure bar mechanism actuated so as to lock the door from the outside, that by simply inserting the wrench, 31, through the opening, 30, the shaft, 22, may be rotated from the inside of the door.

45 I provide means for concealing the opening, 30, so as to render it unnoticeable from the inside of the door, which is as follows: A central opening, 32^a, is drilled at the end of the shaft, 22, and tapped during a portion of its length to receive the threaded end 50 of a dummy bolt, 33. The head, 34, of the bolt, 33, is formed by the machinist, who contours the device so as to be as nearly identical with the heads of the other bolts 55 appearing on the inside of the door, and the outer extremity of the opening, 30, is countersunk, as at 35, to simulate the ordinary countersinking of the bolt heads within the vault door.

60 Should the head, 34, not be sufficiently large to completely cover the opening, 30, the size of which is determined by the necessary breadth of the wrench, 31, a washer, 36, may be secured to the under side of the

head, of such size that it will fit snugly 65 within the countersunk opening, 35, and of such material as to match the vault door.

It will be understood that other means might be used to accomplish the same object, providing that it is of sufficient size 70 to cover the opening, 30, and may be so secured in place as to resemble some common part of the vault door.

Various means may be employed for releasing the hand wheel, 25, from engagement 75 with the shaft, 22, and each will preferably include the following elements:

1. A dog or key, or equivalent device, for forming a connection between the hand wheel, 25, and the shaft, 22, and which is 80 capable of movement to a position where it no longer engages both at the same time.

2. An instrument having an operative connection with the dog or key and extending through the gear box or into the gear 85 box to a position where it is accessible from the inside of the vault door.

The latter device may be external of the shaft, 22, although I find that in practice it is ordinarily preferable to journal it in the 90 shaft, as in the form of my invention shown in the drawings, which I will now describe.

The shaft, 22, is drilled from its inner end with a central opening, 37, extending into that portion of the shaft ordinarily encompassed by the hub, 26. (See Figs. 2 and 4.) 95 A transverse slotted opening, 38, is then cut through the center of the shaft, and joins the opening, 37. The hub, 26, is reamed out as at 39 for a portion of its length, and 100 a pair of diametrically opposed keyways, 40, are cut in that portion of the hub adjacent the reamed opening, 39, to a depth corresponding to the depth of the same.

A key, 41, is extended through the opening, 38, and is of such length that its end will be snugly received within the reamed opening, 39, or within the keyways, 40, according to its position longitudinally of the shaft, 22. When its ends are received in the 110 keyways, 40, it will be seen that the key, 41, serves to connect the hand wheel, 25, with the shaft, 22, and when it is moved to position where its ends are received in the reamed opening, 39, the hand wheel, 25, will 115 be freely rotatable around the shaft, or the shaft may be freely rotated within the hand wheel.

A release rod, 42, is extended through the opening, 37, and threaded at its outer end 120 into the key, 41, as shown in Fig. 2. The rod, 42, is of such length that its other end extends partially into the opening, 32. This end is threaded as shown and a wrench, 43, is provided having a threaded socket, 44, 125 adapted to extend within the opening, 32, and receive the threaded end of the rod, 42.

The dummy bolt, 33, serves to retain the

release mechanism in its operative position wherein the key, 41, engages both the hand wheel, 25, and the shaft, 22.

Should a banker upon being locked within his vault find that the burglar has not only locked the pressure bars, but has locked the hand wheel as well, he can then remove the dummy bolt, 33, insert the wrench, 43, thread it onto the end of the rod, 42, and thereupon withdraw the key, 41, from engagement with the keyways, 40, by pulling upon the wrench.

It will be seen that the rod, 42, may be formed as a part of the wrench, 43, leaving only the key, 41, permanently in place within the shaft, 22. The key, 41, and rod, 42, might be formed integrally as a simple bar sliding in a keyway extending the full length of the shaft, 22.

The details of construction of the various devices involved in my invention will vary according to the type of pressure bar system to which they are attached. For instance, in Fig. 7, there is shown a portion 25 of a pressure bar mechanism in which the vertical connecting shaft, 12^a, is provided with a bevel gear, 45, registering with a bevel gear, 46, on the end of the hand wheel shaft, 47, which, in this case, extends only 30 through the cover, 20^a, of the gear box, 11^a. The shaft, 12^a, being in the same vertical plane with the shaft, 47, it would be difficult to provide a wrench which could be extended around the shaft, 12^a, and a gear, 35 48, is therefore provided, having the hub journaled in the rear wall of the gear box, said gear meshing with the gear, 45, and 40 provided with slots, 49.

The dummy bolt, 33^a, is threaded into the hub of the gear, as shown, and a rod, 50, having an offset portion, 51, to encircle the vertical shaft, 12^a, partly serves the function of the rod, 42. A second rod, 52, is extended 45 through the shaft, 47, and has on its end a key, 41^a, extending through the slot, 38^a, in the shaft, 47, in the same manner as the construction described in Fig. 1.

The inner end of the rod, 52, has a disk head, 53, the periphery of which is received 50 by the bifurcated end, 54, of the rod, 50. Thus the rod, 52, is allowed to turn while the rod, 50, which can not turn by reason of the presence of the shaft, 12^a, is allowed to remain stationary. At the same time, 55 when the rod, 50, is pulled outwardly, the rod, 52, will be drawn with it. The rod, 50, is provided with a threaded end to receive the wrench, 43, in the same manner as described in Fig. 2.

Where a hand wheel having a squared hub opening, to fit a squared shaft, is used, the opening may be bushed and the shaft turned down on a lathe, in order to obtain a rotatable connection between the two.

Some changes may be made in the construction and arrangement of the parts of my invention without departing from the real spirit and purpose of my invention, and it is my intention to cover by my claims any modified forms of structure or use of 65 mechanical equivalents which may be reasonably included within their scope.

I claim as my invention:

1. In combination with a vault door having a pressure bar actuating shaft, and a 75 hand wheel having a hub received over the outer end of the said shaft; an element contained within the hub and adapted to be moved from position where it forms a driving link between the hub and the shaft, to 80 a position where it will allow free rotation of the hand wheel and shaft relative to each other, and means enclosed within the shaft for moving said element from one to the other of said positions, said means being accessible from within the vault door.

2. In combination with a vault door having a pressure bar gear box secured to the outer face thereof, a pressure bar hand wheel shaft extending through said gear box 90 and a hand wheel having a hub received on the outer end of said hand wheel shaft; an element contained within said hub adapted to be moved from position where it forms a driving link between said hub and the shaft, to 95 a position where it will allow free rotation of the hand wheel and shaft relative to each other, a free passageway being provided through the gear box and door to allow access to said element.

3. In combination with a vault door having a pressure bar gear box secured thereto, on its outer side a pressure bar hand wheel shaft journaled in said gear box, and a hand wheel received on the outer end of 105 said shaft, means for connecting and disconnecting said hand wheel in driving engagement with and from said shaft, said means being operable from the inner side of the vault door.

4. In combination with a vault door having a pressure bar gear box secured thereto, a pressure bar hand wheel shaft journaled in said gear box, and a hand wheel received on the outer end of 115 said shaft, means for connecting and disconnecting said hand wheel in driving engagement with and from said shaft, a passageway being provided through the gear box and door to allow access to said means, and an element having an outer configuration similar to other appendages contained on the inner face of the door, received in and concealing the inner extremity of said passageway.

5. In combination with a vault door having a pressure bar gear box secured to the outer face thereof, a hand wheel shaft journaled in said gear box, the inner end of said

hand wheel shaft terminating short of the inner surface of the door and being provided with a transverse slot, the door being provided with an opening registering with the inner end of said shaft; an element having on its inner end a configuration similar to that of other appendages carried by the inner face of the door, said element serving to close and conceal the inner extremity 10 of said opening.

6. In combination with a vault door having a pressure bar gear box secured thereto, on its outer side a pressure bar hand wheel shaft journaled in said gear box, a gear on said shaft within the box, and a hand wheel received on the outer end of said shaft, means for connecting and disconnecting said hand wheel in driving relation with and from said gear, a passageway 15 being provided through the door and into the gear box to allow access to said means for actuating the same from the inner side of the door.

7. In combination with a vault door having a gear box secured thereto on its outer side, a pressure bar hand wheel shaft journaled in said gear box, a hand wheel received on the outer end of said shaft, and a gear on said shaft within the box; an 20 element contained within the shaft for connecting and disconnecting said hand wheel in driving relation with and from said shaft,

a passageway being provided through the door to allow access to said element.

8. In combination with a vault door having a gear box secured thereto on its outer side, a pressure bar hand wheel shaft journaled in said gear box, a hand wheel received on the outer end of said shaft, and a gear on said shaft within the box; an 25 element longitudinally slidable within said shaft, for connecting and disconnecting said hand wheel in driving relation with and from said gear, a passageway being provided through the door to allow access to 30 said element for actuating it.

9. In combination with a vault door having a pressure bar gear box secured to the outer face thereof, a hand wheel shaft journaled in said gear box, the inner end of said hand wheel shaft terminating short of the inner surface of the door, the door being provided with an opening registering with the inner end of said shaft; an element having on its inner end a configuration similar to that of other appendages carried by the inner face of the door, said element serving to close and conceal the inner extremity 45 of said opening.

Signed at Sioux City, in the county of 50 Woodbury, and State of Iowa, this 24th day of August, 1925.

ROBERT L. SHEETZ.
